E. D. DANIELSON.

BRICK CARRIER.

APPLICATION FILED DEC. 30, 1916.

1,249,723.

Patented Dec. 11, 1917.

UNITED STATES PATENT OFFICE.

EUGENE D. DANIELSON, OF BUFFALO, NEW YORK.

BRICK-CARRIER.

1,249,723.

Specification of Letters Patent.

Patented Dec. 11, 1917.

Application filed December 30, 1916. Serial No. 139,731.

To all whom it may concern:

Be it known that I, EUGENE D. DANIELSON, a citizen of the United States, residing at Buffalo, in the county of Erie and State 5 of New York, have invented certain new and useful Improvements in Brick-Carriers; and I do hereby declare the following to be a full, clear, and exact description of the invention, such as will enable others skilled 10 in the art to which it appertains to make and use the same.

This invention relates to a brick carrier and has for its primary object to provide a device of this character whereby a single 15 row of bricks may be quickly and readily picked up and carried from place to place.

Another object of the invention is to provide a brick carrying device which may be readily grasped within one hand and readily 20 and quickly actuated by the same hand to open and close the clamping jaws of the device over a single row of bricks.

A further object of the invention is to provide a carrier which can be readily and 25 quickly adjusted to either increase or decrease the carrying capacity thereof.

With these and other objects in view as will appear as the description proceeds, the invention comprises the various novel features of construction, combination and arrangement of parts as will be more fully described hereinafter and set forth with particularity in the appended claims.

Referring to the drawings,

30 Figure 1 is a side elevation of my improved brick carrier, the actuated position of said carrier being shown in dotted lines.

Fig. 2 is a vertical transverse sectional view taken on the line 2—2 of Fig. 1 looking 40 in the direction of the arrow.

Fig. 3 is a plan view of the device, one end thereof being broken away.

Similar characters of reference are used 45 to denote like parts throughout the accompanying drawings and the following description.

Referring more particularly to the drawings, my improved brick carrier is shown to consist of an elongated frame 1 that embodies 50 elongated members or bars 2 and 3 that are adjustably connected together through the medium of bolts 4 that pass vertically through the overlapping portion of the inner ends of said bars, each of these bolts 4 being provided with a thumb nut 5 whereby the bars 2 and 3 may be rigidly

clamped together. As shown each of the bars 2 and 3 is provided with a series of spaced perforations 6 and 7 that are adapted to align with each other to receive the bolts 60 4, the central portion of those perforations intermediate the bolts 4 are aligned and have positioned therethrough the shank 8 of a finger ring 9, the shank being held in place by a nut 10.

65 The outer end of each of the bars 2 and 3 is each provided with a transversely perforated bearing 11 through which passes a pivotal pin 12 that is designed to pivotally connect the right angular brackets 13 on opposite sides of the bearing 11, these right angular brackets 13 being carried by and fixed to inwardly projecting arms 14 that are designed to normally overlap and rest upon the upper surfaces of the bars 2 and 3 70 respectively.

75 The depending portions 15 of each pair of right angular brackets 13 have attached thereto a hand plate or clamping jaw 16.

From this arrangement and construction 80 it will be apparent that each of the arms 14 and the clamping jaws 16 are connected together and fixed in angular relation to each other and pivotally mounted upon the outer ends of the bars 2 and 3 so that in their 85 pivotal movement they will always maintain the same fixed angular relation.

Each of the arms 14 is also provided with a series of perforations 17 through which bolts 18 are passed, said bolts also extend 90 through a hinge member 19 and serve to securely hold it in place upon the arm 14. By the provision of the series of perforations 17, the hinge member 19 may be adjusted longitudinally of the arm 14 to correspond to the adjustment of the bars 2 and 3 with respect to each other.

95 Each of the hinge members 19 has one end of a link 20 pivotally connected to it as at 21, the opposite end of the link 20 being pivotally connected to one end of the handle 22 as indicated by the numeral 23. As shown the opposite ends of the handle 22 are slotted at 24 to receive the upper pivotal ends of the links 20.

100 When it is desired to use the carrier to pick up a single row of bricks, the handle is grasped in one hand, and a finger of the same hand inserted within the finger ring 9 whereby the handle may be moved inwardly toward the finger ring sufficiently 105 to cause the clamping jaws to be moved

outwardly to a vertical position, whereupon the jaws may be placed over the opposite ends of the row of bricks so that when the finger has been disengaged from the ring 9 and the handle lifted upwardly, the jaws will be moved inwardly and clamped against the row of bricks and held in clamped engagement therewith through the medium of the weight of the bricks supported within 10 the carrier.

When it is desired to release the bricks from the carrier, it is simply necessary to grasp the finger ring and move the handle inwardly toward the finger ring to release 15 the clamping jaws from the row of bricks. This may be accomplished at any time found desirable, irrespective as to whether the bricks within the carrier are supported in mid air or whether the device with the bricks 20 in it have been placed upon the ground.

From the foregoing description it will be apparent that the device can be readily and quickly adjusted to either increase or decrease the carrying capacity and is one by 25 which the bricks may be readily and quickly picked up and carried from place to place.

What I claim is:—

1. A brick carrier comprising an elongated adjustable frame member, a pair of clamping jaws mounted one at each end of said adjustable frame member and disposed at right angles thereto, an arm integral with and extending in at right angles to each clamping jaw member and adapted to overlie said frame member, a hinge mounted on each inwardly extending arm and adjustable longitudinally thereof, a handle, and a link pivotally connected to each hinge member and to the opposite ends of said handle.

2. A brick carrier comprising an elongated adjustable frame member, a pair of clamping jaws mounted one at each end of said frame member and disposed at right angles thereto, an arm integral with and projecting inwardly from each clamping jaw and adapted to normally overlie said elongated frame member, a handle, links pivotally connected to the opposite ends of said handle and adjustably connected to said inwardly extending arms, a finger ring having a shank removably disposed through said elongated frame member and disposed beneath said handle whereby the finger ring may be grasped with one finger with the same hand that is used to grasp the handle 50 to actuate said clamping jaws, and means for clamping said finger ring and the intermediate portion of said frame member together.

3. A brick carrier comprising a pair of 60 superimposed elongated bars, each provided longitudinally with a series of registering apertures, a clamping bolt disposed through both of said bars adjacent the inner end of each bar, a finger ring having a shank removably disposed through said bars intermediate said clamp-bolts and serving to hold that portion of the bars together, a jaw pivotally mounted on the outer end of each bar, a handle, and a link connecting each jaw with 65 said handle.

In testimony whereof I have signed my name to this specification in the presence of two subscribing witnesses.

EUGENE D. DANIELSON
